UNITED STATES PATENT OFFICE.

FREDERICK D. FRY, OF DANBURY, CONNECTICUT, ASSIGNOR OF ONE-HALF
TO THEODORE H. BENEDICT, OF SAME PLACE.

WIRE-TWISTING MACHINE.

SPECIFICATION forming part of Letters Patent No. 398,888, dated March 5, 1889.

Application filed April 28, 1888. Serial No. 272,114. (No model.)

To all whom it may concern:

Be it known that I, FREDERICK D. FRY, a citizen of the United States, residing at Danbury, in the county of Fairfield and State of Connecticut, have invented certain new and useful Improvements in Wire-Twisting Machines; and I do hereby declare the following to be a full, clear, and exact description of the invention, such as will enable others skilled in the art to which it appertains to make and use the same.

My invention relates to the manufacture of hat-wires and similar articles, and has for its object to produce a machine that will sever the hat-wires from the roll of wire that is fed to the machine, and will impart a peculiar twist to each wire, so that when taken from the machine each piece of wire will have been bent to approximately the shape of a finished hat-wire, the sides being highest and the ends having the required set for the front and rear of the hat-brim, the amount of set depending upon the amount of twist imparted to the wire. In order to produce wires of this class of uniform size, shape, and set, and at great speed, I have devised the novel machine which I will now describe, referring by numbers to the accompanying drawings, forming part of this specification, in which—

Figure 1 is a front elevation of the entire machine; Fig. 2, a rear elevation thereof; Fig. 3, a plan view; Fig. 4, a right end elevation; Fig. 4^a, a detail section at the right end of the machine looking outward, showing one of the cams in elevation; Fig. 5, a section on the line *x* *x* in Fig. 3, looking toward the left; Fig. 6, a section on the line *y* *y* in Fig. 3, looking toward the right; Fig. 6^a, a detail cross-section on the line *z* *z* in Fig. 6; Fig. 7, a detail view illustrating the manner of adjusting the holding-jaws and the twisting-heads. Figs. 8, 9, and 10 are respectively a side elevation, front elevation, and plan view of the sliding feeding device, the jaws being in the closed position. Fig. 11 is a plan view corresponding with Fig. 10, except that the jaws are in the opened position; Fig. 12, a side view of the stationary standard carrying the left holding-jaws, the view being from the right in Figs. 1 and 3, the view also showing the operation of the cutting device; Fig. 13, an edge view

corresponding with Fig. 12. Figs. 14, 15, 16, 17, and 18 are detail views illustrating the construction of the cutting device. Fig. 19 is a side view of one of the movable standards carrying a pair of holding-jaws, one of the side plates being removed; Fig. 20, a view of the side plate detached. Fig. 21 illustrates in plan and side elevation the stationary member of a pair of holding-jaws detached. Fig. 22 illustrates in plan and side elevation the movable member of a pair of holding-jaws detached. Fig. 23 is a side view of one of the twisting-heads, showing also the adjusting-gears beneath for the twisting-heads and holding-jaw standards; Fig. 24, an edge view of one of the twisting-heads detached; Fig. 25, a central section corresponding with Fig. 24. Figs. 26, 27, and 28 are detail views of parts of a twisting-head detached. Fig. 29 shows the brake detached. Fig. 30 illustrates in both end and side elevation the movable jaw of one of the twisting-heads detached. Fig. 31 illustrates in a similar manner the stationary jaw of one of the twisting-heads detached. Fig. 32 illustrates the guide in each twisting-head through which the wire passes, and in which the jaws are placed transversely. Fig. 33 illustrates in end and side elevation the collar which operates the brake, and Fig. 34 is a detail of the twisting-gear.

Similar numbers denote the same parts wherever they appear in the drawings.

1 denotes frame-work, supported by legs 2, both frame-work and legs being of any suitable or preferred construction. 3 is the main shaft, journaled under the frame-work, power being applied by a belt (not shown) running over a pulley, 4, on said shaft.

5, 6, 7, 8, 9, and 10 are cams on shaft 3, the purposes of which are as follows: 5 operates the sliding feeding device, 6 operates the feed-jaws, 7 operates the holding-jaws, 8 operates the twisting-heads, 9 operates the brakes in the twisting-heads, and 10 operates the cutting device. The construction and operation of these parts and the intermediate connections between the operative parts and the cams will now be described in detail.

11 is the standard which carries the stationary holding-jaws; 12, standards carrying movable holding-jaws; and 13 standards car-

rying the twisting-heads. The adjustment of standards 12 and 13 will be described later in connection with the sliding feeding device.

Turning now to Figs. 19 to 22, inclusive, I 5 will describe the construction and operation of the holding-jaws carried by standards 12. It should be noticed, however, that the construction and operation of the holding-jaws carried by standard 11 is precisely the same 10 as those carried by standards 12, the only difference being that standard 11 is not movable, and that this standard also carries the cutting device, all of which will be more fully explained.

15 14 denotes side plates, which are firmly secured to standards 11 and one to standard 12. The standards are provided with holes 15, in which a rock-shaft, 16, is journaled.

17 denotes the stationary holding-jaws, 20 three in number, which are rigidly secured to blocks 18 between the side plates.

19 denotes the movable holding-jaws, which are carried by oscillating plates 20, pivoted between the side plates, as clearly shown in 25 Figs. 19 and 12. The style of jaws which I preferably adopt is clearly illustrated in Figs. 21 and 22. At the forward ends of the jaws are notches 21, through which the wire passes. These notches may be made in any suitable 30 form to grasp and hold the wire firmly.

22 is a plate secured at the side of the stationary jaw, and having inclines 23, which engage corresponding inclines on the movable jaw to insure that the jaws register when they 35 are closed together and to prevent the possibility of the wire slipping out when the jaws are at their open position. The movable jaws, three in number, are all operated by means of cams 24 on rock-shaft 16, the action of said 40 cams being to force the jaws tightly upon the wire when the cam is oscillated toward the left, as in Fig. 19. When the backward movement of the rock-shaft and cams takes place, the jaws open instantly, oscillating plates 20 45 being so pivoted as to drop to the opened position as soon as the cam moves backward. A spring may, of course, be inserted to throw the jaw to the open position if desired. This, being a common expedient, has not been illustrated in the drawings. The cams are secured 50 to shaft 16 by means of splines 24^a, which engage a groove in the rock-shaft, leaving the cams operating in connection with the movable standards free to slide on said rock-shaft.

55 25 denotes a crank-arm secured to the rock-shaft, and connected by means of a rod, 26, to a lever, 27, pivoted to a suitable portion of the machine, as at 28, (see Fig. 4,) and having at its inner end a roller engaging a groove (not 60 shown) in cam 7, the groove being so laid out that by means of the intermediate connections just described each rotation of cam 7 will impart a forward-and-backward movement to rock-shaft 16, thereby closing the jaws 65 and opening them again, the machine being so organized in this instance that the movements of the rock-shaft toward the front in

Figs. 1 and 3 act to open the jaws, and the movements toward the back or toward the left in Fig. 19 act to close them.

70

Turning now to Figs. 23 to 34, inclusive, I will describe the construction and operation of one of the twisting-heads.

29 denotes the stationary twisting-jaw, and 30 the movable twisting-jaw. The grasping 75 surface of these jaws is preferably an independent piece of chilled steel dovetailed into place, as clearly shown in Figs. 30 and 31. One of the members—in the present instance the stationary jaw—is provided with plates 31, 80 having inclines 32, which are engaged by corresponding inclines on the movable jaw to insure that the jaws register when they are closed together and to prevent the possibility of the wire slipping out when the jaws are at 85 their open position. The jaws are provided with notches in their grasping-surfaces, in which the wire lies as it is grasped.

33 denotes a sleeve, having a longitudinal opening, 34, through which the wire passes, 90 and a transverse opening, 35, in which the jaws lie. The opposite ends of the sleeve are journaled in side plates, 36, which are bolted rigidly to standards 13. The lower ends of the side plates are made thicker and are provided 95 with recesses 37 to receive brakes 38.

Just within the side pieces are disks 39, which, for convenience in description, I have termed "outer" disks, each of which is provided with a central opening through which 100 the sleeve passes and an eccentric slot, 40. These slots are engaged by rollers 41, carried by pins projecting from the ends of the movable jaws. (See Fig. 30.) Just within disks 39 are disks 42, which I term the "inner" 105 disks, also provided with central openings, through which the sleeve passes, and with slots 43, extending across the central openings in which the jaws lie. Between disks 42 is a pinion, 44, having a central opening similar 110 to the disks through which the sleeve passes, and a slot, 45, to receive the jaws, this slot being similar to slots 43 in the inner disks, except that the portion of said slot which receives the movable jaw is not as long as the 115 slots in the disks, the movable jaw being provided with a notch, 46, the bottom of which engages the end of slot 45 in the pinion, the portions of the movable jaw on the opposite sides of the notch engaging the 120 longer slots 43 in the disks, so that the parts are held firmly together when assembled. The twisting-heads are operated by gears 47 on oscillating shaft 48, which engage pinions 44.

49 is a pinion on shaft 48, which is engaged 125 by a segmental gear, 50. Shaft 48 is journaled in brackets 51, which project backward from the frame-work, and the segmental gear is rigidly attached to a short shaft journaled in a box, 52, which is also carried by a bracket 130 projecting from the frame-work.

53 is an arm made integral with and projecting backward from the segmental gear and provided with a slot, 54, for the attach-

ment of a rod, 55. The lower end of this rod is pivoted to an arm, 56, projecting outward from a slide, 57, which is adapted to move vertically in ways 58 in a bracket, 58^a, depending from the frame-work of the machine, as clearly shown in Fig. 6^a. Slot 54 is formed in an arc of a circle of which the pivotal point of rod 55 to arm 56 is the center. A bolt, 59, passes through the rod and through slot 54, and is engaged by a lock-nut, 60, whereby the parts are locked in position after adjustment.

61 is a gage on arm 53, by which bolt 59 is set to give any desired number of turns or fractional parts of turns to the wire in operation.

It will of course be understood that the farther inward rod 55 is set in slot 54 the greater will be the oscillation of the segmental gear and the greater the amount of twist given to the wire. As shown in Figs. 5 and 6, rod 55 is set to give the least possible twist to the wire. It is desirable that this adjustment should be effected in as simple a manner as possible, for the reasons that no two coils of wire work just alike, and that changes in the styles of hats necessitate frequent changes in the set of the wires.

Vertical reciprocatory motion is imparted to the slide by means of a roller, 62, (see dotted lines, Fig. 5,) carried by a pin at the lower end thereof and engaging groove 63, in cam 8 on the main shaft. It will be seen that each rotation of cam 8 causes an upward-and-downward movement of slide 57, which in turn causes an oscillation in each direction of the segmental gear and, through the intermediate connecting mechanism just described, an oscillation in each direction of the twisting-heads, it being of course understood that the two twisting-heads are of identically the same construction. The brake is operated by means of rock-shaft 64, which is journaled in the standards 11 and 12, which carry the holding-jaws. At the outer end of this shaft (see Fig. 4) is a crank-arm, 65. A rod, 66, connects the crank-arm with a slide, 67, moving in ways at the end of the frame-work. (See dotted lines, Fig. 4.) A roller, 68, carried by a pin at the lower end of the slide, engages a groove in cam 9, the construction and arrangement being such that each rotation of cam 9 will cause an oscillation of rock-shaft 64 in each direction, whereby the brake is raised and lowered.

Turning again to Figs. 23, 24, and 25, the connection of the brake with the rock-shaft will be clearly shown.

69 is a sleeve on the rock-shaft, which lies loosely in an opening, 70, in standard 13. The rock-shaft is provided with a groove and the sleeve with a key or feather, 71, engaging said groove, whereby the sleeve is securely locked to the rock-shaft to turn therewith, but at the same time is left free to slide longitudinally thereof in adjusting the twisting-heads, as will presently be explained.

72 is a link, the opposite ends of which are

connected to the sleeve and to the brake, whereby the latter is forced upward and downward by the oscillation of the rock-shaft.

The operation of this portion of the machine independently of the feeding and cutting devices is briefly as follows: After the wire has been passed through the three pairs of holding-jaws and through the two twisting-heads, the first portion of the mechanism to engage the wire is the three pairs of holding-jaws actuated by cams 24 on rock-shaft 16. An instant later the brakes, actuated by rock-shaft 64, are forced upward and engage the peripheries of the outer disks, 39, thereby locking said disks for an instant against rotary movement. By this time the segmental gear, actuated by cam 8 and slide 57, will have begun to turn, oscillating shaft 48, carrying gears 47, engaging pinions 44. It will, of course, be understood from Figs. 25 to 34, inclusive, and the description already given that inner disks, 42, must rotate with the pinion and will carry the jaws around with them. As outer disks, 39, are held against rotation by the brakes, it follows that the rotation of the jaws carried by the inner disks and the pinion must cause rollers 41, carried by pins at the ends of the movable jaws, to travel inward in eccentric slots 40 in the outer disks, thereby clamping the movable jaws down firmly upon the wire, this position being clearly shown in Figs. 23 and 25. An instant later, through the action of cam 9, the intermediate mechanism, and rock-shaft 64, the brakes will be released and will drop away from the outer disks, leaving said disks free to turn with the inner disks and the pinion, but without releasing the grip of the jaws upon the wire. As the piece of wire being acted upon is now clamped firmly by the three pairs of holding-jaws, and also clamped firmly by the jaws in the twisting-heads midway between each pair of holding-jaws, it follows that the wire must be twisted by the rotation of the twisting-heads so long as the movement of the oscillating shaft 48 in that direction continues. The action of cams 8 and 9 is so timed that at the instant the oscillation of shaft 48 in that direction ceases and the return movement commences the brakes actuated by cam 9 will again engage the outer disks and lock them for an instant against movement with the inner disks, pinion, and jaws. This second locking of the outer disks will cause rollers 41 to travel outward in eccentric slots 40, thereby throwing the movable jaw out of contact with the wire, so that the entire twisting-head is free to rotate about the wire, but without contact therewith during the backward movement. The holding-jaws, actuated by rock-shaft 16, cam 7, and intermediate mechanism, already fully described, release the wire an instant before the jaws in the twisting-heads release it, so that the wire is now free. Just before the releasing of the wire by the holding-jaws and the jaws of the twisting-heads

the feeding mechanism, or, as it may be termed, the "sliding, feeding, and measuring device," will have moved forward and seized the end of the wire.

5 Turning now to Figs. 2, 8, 9, 10, and 11, the sliding feeding device will be found clearly illustrated. This device consists of upper and lower plates, 73 and 74, and a standard, 75, to which both plates are secured. The lower 10 plate is provided with downwardly-projecting flanges 76, which rest against the outer edges of the top of the frame-work, being held in position by plates 77, secured to the bottom thereof, which, in connection with the flanges 15 and lower plate, inclose flanges 78 at the edges of the frame-work, this construction being clearly shown in Fig. 23, which illustrates it as applied to one of the twisting-heads, the construction of this portion of the sliding 20 feeding device, the standards of the twisting-heads, and the standards of the holding-clamps being the same.

79 denotes the feed-jaws, which are pivoted to the upper plate and are held at their open 25 position by means of springs 80, bearing against their shanks, as clearly shown in Figs. 10 and 11.

81 is a shaft journaled in the upper and lower plates and having at its upper end an oval cam, 82, lying between the shanks of the 30 jaws and acting to clamp the jaws firmly upon the wire when the greatest diameter of the cam is turned transversely to the shanks, as shown in Fig. 10.

35 83 is a pin projecting outward from shaft 81 and adapted to be engaged by fingers 84 and 85, projecting upward from a longitudinally-sliding shaft, 86. This shaft may be reciprocated in any suitable manner. In the 40 present instance I have shown it as connected by means of an arm, 87, with a sliding shaft, 88, held in suitable guides, 89, at the side of the frame-work.

90 is a lever pivoted to a bracket, 91, depending from the frame-work. The upper 45 end of this lever is connected by a link, 92, with the rear end of sliding shaft 88, and is provided at its lower end with a roller, (indicated in Fig. 1,) which engages a groove, 93, in cam 6. The groove is so laid out that each rotation of cam 6 will cause a movement of shafts 86 and 88 in each direction. The inner end of shaft 86 is supported in a plate, 94, attached to the standard 11 of the stationary holding-clamp, and its outer end is supported in a bracket, 95, at the outer end of the frame-work. The sliding feeding device is caused to reciprocate in the manner which I will now describe.

60 96 (see Figs. 1 and 2) is a rod the outer end of which is pivoted to the inner end of a lever, 97, and the inner end to the upper end of an oscillating lever, 98, the lower end of which is pivoted to ears 99 on a suitable bracket or 65 secured to the floor beneath the machine, as shown in the drawings. Lever 98 is provided with a roller, 100, engaging groove 101 in cam

5 upon the main shaft, each rotation of said cam acting to impart a movement of said lever in each direction. Lever 97 is fulcrumed 70 on an adjustable block, 102, supported in a guide, 103, under the frame-work. Lever 97 is provided with a slot, 104, having at its side a gage, 105, the purpose of which will presently be explained. 75

106 is a bolt passing loosely through block 102 and slot 104, and 107 is a lock-nut engaging the end of the bolt and adapted to be screwed down upon lever 97, thereby clamping it firmly to the bolt, so that the bolt will 80 turn in the block when the lever oscillates. At the outer end of lever 97 is a link, 108, the inner end of which is pivoted to any suitable portion of the sliding feeding device—in the present instance standard 75. As shown in 85 Figs. 1 and 2, the sliding feeding device is at its retracted position. A half-rotation of cam 5 by means of the intermediate mechanism just described will throw the sliding feeding device to the opposite extreme of its movement—that is, clear forward to standard 11, which carries the stationary holding-jaws and the cutter.

Turning now to Figs. 12 to 18, inclusive, I will describe the operation of the cutter. As 95 already stated, standard 11 is similar in construction to standards 12; but only one plate 14 is used, plate 109 being substituted for the other plate 14, and attached to the standard in the same manner. Plate 109 is provided 100 with a threaded opening, 110, which is engaged by the inner end of threaded sleeve 111 and with transverse slots 112, which receive pins 113 on the cutters 144. These cutters slide in transverse groove 115 in a plate, 105 116, which is rigidly secured to plate 109, the position of the parts after assembling being clearly shown in Fig. 13.

117 is a disk journaled on sleeve 111 and provided with curved slots 118. This disk 110 turns freely on the smooth portions of the sleeve, and is held in position thereon by flange 119 at the outer end thereof. Pins 133 on the cutters pass entirely through slots 112 in plate 109 and engage the curved slots 118 115 in the disk. The disk is oscillated on the sleeve to move the cutters in and out by means of an arm, 120, rigidly secured thereto, the outer end of which is pivoted to a rod, 121. The lower end of the rod is pivoted to the 120 outer end of a lever, 122, which is itself pivoted to one of the legs of the machine, as shown in Fig. 2. The inner end of this lever bears against eccentric cam 10 on the main shaft, the weight of the inner end of the lever being sufficient to draw it down when the short diameter of the eccentric cam is at the top. When the long diameter of the eccentric cam moves upward, its action is to raise the inner end of lever 122, which of course throws 130 down the outer end, and by means of arm 120 turns disk 117 on the sleeve, and by means of the engagement of pins 113 with the curved slots in the disk forces the cutters inward,

thereby severing the wire. It will be seen that each rotation of eccentric cam 10 moves the cutters to their retracted position, severs the twisted wire, and then causes the cutters to move back to their retracted position. At the instant the completed wire is severed the sliding feeding device will move up to the cutters, the jaws thereof passing into sleeve 111. By this time the cutters will have moved to their retracted position, so that the jaws can pass forward through the sleeve and through opening 123 in plate 116 close up to holding-jaws 17 and 19. It will be noticed from the position of the cutters and cam 24, which operates the movable holding-jaw in standard 11, that there must be a stump of wire left between the cutters and the holding-jaws after the twisted wire has been severed. This stump (not shown in the drawings) is grasped by the feed-jaws 79. The operation of these jaws is as follows: At the instant that the feed-jaws, still in their open position, as shown in Fig. 11, have passed through sleeve 111 and into opening 123 in plate 116 pin 83 on shaft 81 will be engaged by finger 84 on sliding shaft 86, which will at that instant move toward the left, as seen in Fig. 1, thereby turning shaft 81 and carrying cam 82 from the position shown in Fig. 11 to the position shown in Fig. 10. This closes the jaws firmly upon the wire. As the position of cam 82 at this instant is such that the shanks of both jaws as acted on by springs 80 press equally upon the cam, it follows that the jaws must remain in the closed position and clamp the wire firmly until they are allowed to open again by the turning of the cam by another movement of sliding shaft 86. The instant the wire has been grasped by the jaws the return movement of the sliding feeding device commences. This continues until the predetermined length of wire has been drawn forward through the holding-jaws and twisting-heads. The instant the return movement—that is, the movement toward the left in Fig. 1—of the sliding feeding device is completed the three pairs of holding-jaws engage the wire. The jaws in the twisting-heads also engage it and commence the twisting of a second hat-wire, the cutters sever the wire last twisted, and just an instant after the movement of the sliding feeding device toward the left is completed pin 83 on shaft 81 is engaged by finger 85 on sliding shaft 86, which at this instant moves toward the right and acts to turn cam 82 from the position shown in Fig. 10 to that shown in Fig. 11, thereby opening the feed-jaws again and releasing the twisted wire that has just been severed by the cutters, the severing of the wire by the cutters and the releasing by the feed-jaws being practically simultaneous. The completed wires may be taken from the machine by an attendant or may be allowed to drop. These movements are continuously repeated and produce perfectly-twisted wires of any desired size at a high rate of speed.

As already stated, the twisting of the wire acts to produce the desired amount of set at the front and rear of the hat-brim. Fingers 70 75 84 and 85 are secured to shaft 86 by set-screws, so that they may be readily adjusted by loosening the set-screws, moving the fingers on the shaft, and again tightening up the set-screws.

It will be apparent that a certain relative adjustment of the twisting-heads relatively to the movable holding-jaws must be maintained at all times, and that the throw of the sliding feeding device must be equal to the distance 80 between the right pair of holding-jaws and the stationary holding-jaws—that is to say, the exact amount of wire required for each hat-wire must be drawn forward by each return movement of the sliding feeding device—85 and no matter what may be the length of the wire that is to be made it must be gripped at both ends and midway between the ends, and the two twisting-heads must act midway between the pairs of holding-jaws, one twisting-head being located at all times midway between the stationary holding-jaws and the middle pair of the movable holding-jaws, and the other twisting-heads midway between the other pairs of movable holding-jaws. By 90 "movable" I mean capable of being moved, it being of course understood that the position of the two pairs of movable holding-jaws is only changed when the length of wire produced by the machine is changed. 95 100

It is of course quite practicable to fix the adjustments independently of each other. I have, however, provided an adjusting device which, by slight movement in either direction, will change the adjustment of the two pairs 105 of movable holding-jaws and the two twisting-heads, and will also change the throw of the sliding feeding device, so that it will always correspond with the distance between the right movable holding-jaws and the stationary holding-jaws. 110

As already explained, the standards which carry the twisting-heads and the movable holding-jaws slide upon the top of the framework, which may be of any preferred construction, there being, preferably, two side pieces, as shown in Fig. 23. Each of the movable standards 12 and 13 is provided with a downwardly-projecting lug, 124, to which racks are pivoted, the rack pivoted to the 120 standard carrying the right holding-jaws (seen in dotted lines only in Fig. 7) being denoted by 125, the rack pivoted to the standard carrying the right twisting-head being denoted by 126, the rack pivoted to the standard 125 carrying the central holding-jaws being denoted by 127, and the rack pivoted to the standard carrying the left twisting-head being denoted by 128. The lugs to which these racks are pivoted are provided with base-plates screwed firmly to the under sides of the standards, one of them being shown in Fig. 23. These lugs are so arranged that the racks lie side by side without interference, as shown 130

in Fig. 7. The inner ends of these racks engage a series of gears on a shaft, 129, journaled in the frame-work. These gears are all of a different size, and are so laid out that rotation of shaft 129 will move the standard of the central holding-jaws double the distance that the standard of the left twisting-head is moved, will move the standard of the right twisting-head double the distance that the standard of the central holding-jaws is moved, and will move the standard of the right holding-jaws double the distance that the standard of the right twisting-head is moved. In the drawings I have denoted the gear engaged by rack 125 as 130, the gear engaged by rack 126 as 131, the gear engaged by rack 127 as 132, and the gear engaged by rack 128 as 133. As the distance between the stationary holding-jaws and the right pair of movable holding-jaws must correspond with the throw of the sliding feeding device, I adjust the throw of said device by the same gear denoted by 125, which adjusts the position of the right holding-jaws. This adjustment is effected by a rack, 134, the outer end of which is pivoted to adjustable blocks 102, and the inner end of which is supported in contact with gear 125 by a roller, 135, carried by a suitable bracket depending from the frame-work. (See dotted lines, Fig. 9.)

136 is a disk on the end of shaft 129 at the front of the machine. This disk is provided with holes in its periphery to receive a rod for the purpose of turning it to adjust the standards and feeding device, and after adjustment the parts are locked in position by a pin, 137, which passes through a bracket, 138, secured to the frame-work and engages one of the holes in the periphery of the disk.

40 Turning for an instant again to Fig. 2, it will be noticed that a gage is provided by the side of the slot in lever 97. It will of course be apparent that in the construction shown the throw of the sliding feeding device will 45 be determined by the position of the fulcrum of said lever 97. When it is desired to make a change in the length of wire that is being produced, it is simply necessary to loosen lock-nut 107 and remove pin 137 from disk 136.

50 The disk is then turned in the direction required to lengthen or shorten the wire. The adjustment is of course made when the holding-jaws and the jaws of the twisting-heads are at their open position and the sliding feeding device is at the extreme of its movement 55 toward the right, as seen in Fig. 2—that is, from the rear of the machine. In this position, and as seen in this figure, rotation of disk 136 and the gears toward the right will, by

60 means of rack 134, move block 102 and bolt 106—*i. e.*, the fulcrum of lever 97—toward the left, and will also move the standards of the twisting-heads and movable holding-jaws toward the right. The exact length of wire that 65 will be formed at any position of the parts is indicated by gage 105, which is marked to register with lock-nut 107. When the length

of wire that it is desired to produce is indicated by the gage, the lock-nut is tightened up to clamp lever 97 and bolt 106 together, 70 and pin 137 is passed through bracket 138 and into one of the holes in the periphery of disk 136. This locks the parts in position, and the machine is ready for use.

The operation of the entire machine is 75 briefly as follows: In starting the machine, wire is passed in from the right, as seen in Fig. 1, through the three pairs of holding-jaws and the two twisting-heads, and up to, but not necessarily through, the cutters. If the machine is started with the parts in this position, the holding-jaws first close upon the wire, grasping it firmly at three places. The brakes in the twisting-heads operate, the jaws in the twisting-heads close upon the 85 wire, and the rotation of the twisting-heads midway between the points at which the wire is held by the holding-jaws twists the wire. At the conclusion of the twisting operation the brakes again act, the jaws in 90 the twisting-heads release the wire, the holding-jaws release the wire, and while the twisting-heads are being turned backward the sliding feeding device advances, the feeding jaws grasp the end of the wire, the return 95 movement of the feeding device takes place, and the portion of the wire which has just been twisted is drawn past the cutters, and a sufficient quantity of the wire to form another hat-wire is drawn forward ready to be grasped 100 by the holding-jaws and the twisting-heads. At the instant that the return movement of the feeding device is completed the holding-jaws and the jaws in the twisting-heads again grasp the wire, the operation of twisting the 105 new wire commences, and at the same instant the completed wire is severed by the cutters and released by the fixed jaws, these movements being continuously repeated. Each rotation of the main shaft thus acts to measure 110 the length of a single hat-wire, to sever the wire just completed, and to twist a second wire.

I claim—

1. The combination, with the frame-work, 115 of stationary and movable standards, each of which is provided with a stationary and a movable jaw adapted to hold the wire, a rock-shaft, 16, and stationary and movable cams on said shaft adapted to force the movable 120 jaws into operating position when it is desired to grasp the wire.

2. The combination, with standard 11 and adjustable standards 12, each carrying holding-jaws, of rock-shaft 16, having cams 24, for 125 operating the holding-jaws, the cams which operate the jaws carried by the movable standards being adapted to slide on said shaft.

3. The combination, with standards 13, the twisting-heads and operating mechanism 130 therefor, stationary standard 11, and movable standards 12, of side plates 14, attached to the standards, stationary holding-jaws, movable holding-jaws pivoted between the side

- plates, and cams engaging the movable jaws to throw them to the closed position.
4. The combination, with rock-shaft 16, having cams 24, of standards 11 and 12, side plates secured thereto, in which the rock-shaft is journaled, stationary jaws having inclines 23, and movable jaws actuated by the cams and having inclines corresponding with inclines 23, so that the jaws register in the closed position.
5. The combination, with the standards and side plates, of stationary holding-jaws 17, jaws 19, carried by oscillating plates 20, and cams for oscillating said plates, said jaws having notches at their forward ends to engage the wire and inclines, whereby they are caused to register in the closed position.
6. The combination, with rock-shaft 16, having a groove, and cams 24, secured to said rock-shaft by splines engaging the groove, of stationary and movable standards each carrying a stationary and movable holding-jaw, and side plates on opposite sides of the cams, all arranged so that the movable standards may be adjusted without affecting the operation of the cams and jaws.
7. The combination, with stationary and movable standards 11 and 12 and holding-jaws carried thereby which grasp the wire, of movable standards 13, carrying twisting-heads midway between the holding-jaws, jaws in the twisting-heads, mechanism, substantially as described, for closing the jaws upon the wire, and mechanism, substantially as described, for rotating the twisting-heads while the jaws are holding the wire.
8. The twisting-heads consisting of side plates, 36, sleeve 33, journaled in the side plates, said sleeve having a longitudinal opening to receive the wire and a transverse opening, 35, pinion 44, disks 42, said pinion and disks having a transverse slot registering with the slot in the sleeve, a stationary and a movable jaw lying in said slots, the latter having rollers 41, disks 39, having eccentric slots engaged by said rollers, brakes acting on disks 39, and mechanism, substantially as described, to operate the brakes and to oscillate the pinion, whereby the brakes are caused to engage disks 39, the jaws to engage the wire, and the brakes to release disks 39, and the continued movement to twist the wire until the brakes act again and cause the jaws to release the wire.
9. The combination, with standards 13, side plates, 36, secured thereto, and a sleeve, 33, journaled in the side plates and having transverse slot 35, of pinion 44 and disks 42, having slots corresponding with slot 35, a stationary and a movable jaw lying in said slots, disks 39, also journaled on said sleeve, eccentric slots in said disks, rollers on the movable jaw engaging said slot, brakes engaging disks 39, and a segmental gear engaging the pinion.
10. The combination, with the standard, side plates, sleeve 33, disks 39 and 42, pinion 44, and the jaws, of brakes 38, recessed in the side plates, rock-shaft 64, having a groove, sleeve 69, having a spline engaging said groove, and links 72, connecting said sleeve 70 with the brakes.
11. In a machine for twisting wire, the combination, with the stationary jaw and the movable jaw having rollers 41, of disks 39, having eccentric slots engaged by said rollers, 75 pinion 44 and means for operating it, brakes 38, engaging said disks, and a rock-shaft and links whereby said brakes are caused to engage with disks at predetermined times.
12. In a machine for twisting wire, the combination, with sleeve 33, having a transverse slot, of disks 42 and pinion 44, turning with said sleeve and having transverse slots corresponding with the slot in the sleeve, jaws lying in said slots, and an oscillating gear engaging 85 said pinion, whereby the jaws are operated.
13. The combination, with the holding-jaws and twisting-heads, of an oscillating shaft having gears by which the twisting-heads are oscillated and a pinion, 49, a segmental gear 90 having a slotted arm with a gage, a slide in the frame-work, and a rod, 55, pivoted to said slide and adjustably secured in said slot, whereby the oscillation of the twisting-heads may be regulated to impart more or less twist 95 to the wire.
14. The combination, with the holding-jaw and twisting-head standards and racks pivoted thereto, of shaft 129, carrying gears of diminishing size engaged by said racks, whereby movement of said shaft and gears in either direction will adjust said standards to different sizes of hat-wires, the gears being so laid out that the twisting-heads are kept midway between the pairs of holding-jaws.
15. The combination, with the standards carrying the holding-jaws and twisting-heads and racks pivoted to said standards, of shaft 129, carrying diminishing gears engaged by said racks, and a disk, 136, having openings 100 in its periphery, bracket 138, and a pin engaging said bracket and the openings in the disk, whereby the standards are locked at any desired adjustment.
16. The combination, with standard 11 and plates 109 and 116, of the cutters having pins 113 and an oscillating disk having curved slots engaged by said pins, whereby the oscillation of said disk operates the cutters to sever the wire at predetermined times.
17. Standard 11, plate 109, having slots 112, and plate 116, having grooves 115, in combination with the cutters lying in said grooves, and pins 113, which pass through slots 112 and engage curved slots in oscillating disk 117, as and for the purpose set forth.
18. The combination, with standard 11 and plate 109, having a threaded opening, of sleeve 111, engaging said opening, the cutters having pins 113, and oscillating disk 117, 110 journaled on said sleeve and having slots engaged by said pins.
19. The combination, with standard 11, plate 116, having grooves 115, and the cut-

- ters having pins engaging said grooves, of disk 117, having slots engaged by said pins, arm 120, secured to said disk, lever 122, engaging cam 10, and a rod connecting said lever and arm.
20. The sliding feeding device consisting of upper and lower plates, a shaft journaled in said plates and carrying an operating-cam, and jaws pivoted to one of said plates, whose shanks are engaged, respectively, by springs 80 to open the jaws and by the cam to close them.
21. The combination, with the sliding feeding device having jaws 79, of shaft 81, carrying cam 82 to close the jaws, and a pin, 83, and a finger, 85, carried by a sliding shaft, 86, said fingers engaging pin 83 to open the jaws again at the proper time.
22. Sliding shaft 86, having fingers 84 and 85, in combination with the sliding feeding device carrying jaws 79, a shaft carrying a cam and having a pin, 83, which is engaged by finger 84 to close the jaws upon the wire when the feeding device is at its forward position and by finger 85 to open the jaws when the feeding device is at the opposite extreme of its movement.
23. The combination, with upper and lower plates, 73 and 74, and standard 75, of jaws 79, pivoted to the upper plate, springs 80, acting to throw said jaws to the open position and shaft 81, journaled in said plates and carrying a cam which engages the shanks of the jaws to close them.
24. The jaws and shaft 81, having cam 82 and pin 83, in combination with sliding shaft 86, having fingers 84 and 85, which are engaged by pin 83 at predetermined times to open and close the jaws.
25. The combination, with jaws 79 and shaft 81, having cam 82 and pin 83, of sliding shaft 86, having fingers 84 and 85, sliding shaft 88, to which shaft 86 is connected, lever 90, carrying a roller engaging cam 6, and link 92, connecting said lever to shaft 88.
26. The combination, with the sliding feeding device, cam 5, and lever 98, having a roller engaging said cam, of rod 96, link 108, and lever 97, connected to said link and said rod.
27. The combination, with the sliding feeding device, cam 5, and lever 98, having a roller engaging said cam, of rod 96, link 108, and lever 97, pivoted to adjustable block 102 and connected to said link and said rod.
28. The combination, with the sliding feeding device, levers 97 and 98, rod 96, and link 108, of block 102, to which lever 97 is pivoted, and a rack pivoted to said block and engaging gear 130, whereby the throw of the sliding feeding device may be adjusted.
29. The combination, with block 102, rack 134, and gear 130, of the sliding feeding device, oscillating lever 98, rod 96, pivoted to said lever, link 108, pivoted to the sliding feeding device, and lever 97, pivoted to block 102 and to said rod and link, and provided with a gage, 105, whereby the parts may be set to feed the desired length of wire.
30. The combination, with block 102, rack 134, and gear 130, of the sliding feeding device, oscillating lever 98, rod 96, pivoted to said lever, link 108, pivoted to the sliding feeding device, lever 97, having slot 104 and gage 105, bolt 106, passing through said block and said slot, and a lock-nut engaging said bolt to lock the parts when adjusted.
31. In a wire-twisting machine, the combination, with sets of holding-jaws and intermediate twisting-heads, of a sliding feeding device carrying jaws 79 and operating mechanism arranged and timed, substantially as set forth, whereby each forward movement of the feeding device draws forward the wire last twisted and places new wire in the holding-jaws and twisting-heads ready to be acted upon.
32. The combination, with the holding-jaws, the twisting-heads, the sliding feeding device having jaws 79, cutters 114, and operating mechanism arranged and timed substantially as set forth, whereby a completed hat-wire is severed while the second is being formed.
33. The combination, with the cutters, the sliding feeding device, and operating and connecting mechanism, substantially as described and shown, of oscillating lever 98, rod 96, lever 97, having an adjustable fulcrum, and link 108, connecting said lever with the sliding feeding device.
34. The combination, with the cutters having pins 113, and oscillating disk 117, having slots 118 engaged by said pins, of arm 120, attached to said disk, lever 122, engaging cam 10, and rod 121, connecting said lever and said arm.
35. The combination, with standards 11 and 12 and a stationary and a movable holding-jaw in each standard, of rock-shaft 16, having a groove, cams 24, which actuate the movable jaws and are provided with splines engaging said groove, crank-arm 25 on said shaft, lever 27, having a roller engaging cam 7, and a rod connecting said lever and said crank-arm.
36. The combination, with stationary and movable twisting-jaws, the latter having rollers 41, and disks 39, having slots engaged by said rollers, of brakes 38, engaging said disks, rock-shaft 64, having a groove, sleeve 68, having a spline engaging said groove, links connecting said sleeve with the brakes, a crank-arm on said rock-shaft, a slide having a roller engaging a groove in cam 9, and a rod connecting the crank-arm with the slide.
37. The combination, with sleeve 33, having a transverse slot, disks 42, and pinion 44, having transverse slots registering with the slot in the sleeve, and a stationary and a movable jaw lying in said slots, the latter carrying rollers, of disks 39, having grooves 125 engaged by said rollers, segmental gear 50, having arm 53, a slide having a roller engaging cam 8, and a rod connecting said arm and said slide.

38. The combination, with standards 12 and 13, the holding-jaws and twisting-heads carried by said standards, the feeding mechanism, and block 102, by which it is adjusted, of 5 racks pivoted to said standards and said block, and a shaft carrying gears engaged by said racks, whereby the sliding feeding device and the holding-jaws and the twisting-heads may be so adjusted as to feed the desired length 10 of wire and hold it at both ends and the center and to twist it midway between the points at which it is held.

39. The standards 12 and 13, having lugs 124, racks pivoted to said lugs so as to lie 15 side by side, and block 102, also having a rack pivoted thereto, in combination with a shaft carrying diminishing gears engaged by said racks, the sliding feeding device, and holding-jaws and twisting-heads carried by the standards.

40. The combination, with standard 11, the cutters having pins, sleeve 111, and a disk journaled thereon and having slots engaged by said pins, of the sliding feeding device 25 carrying jaws and operating mechanism arranged and timed substantially as set forth, whereby when the forward movement of the sliding feeding device takes place the jaws enter said sleeve and grasp the end of the 30 wire after the cutters have severed the completed hat-wire.

41. The combination, with standard 11, the cutters having pins, sleeve 111, and a disk journaled thereon and having slots engaged 35 by said pins, of the sliding feeding device, jaws 79 carried thereby, and mechanism, substantially as described, which causes the jaws to grasp the wire at one extreme of its movement and to release it at the other extreme.

40 42. The combination, with the sliding feeding device having jaws which grasp the wire at one extreme of its movement and release it at the other, of cutters which sever the completed hat-wire, holding-jaws which grasp the 45 second wire at both ends and at the center, and oscillating heads which twist the wire midway between the points at which it is grasped, substantially as described.

43. The combination, with the twisting- 50 heads having pinions 44, and oscillating shaft 48, having gears engaging said pinions, and a pinion, 49, of a segmental gear engaging pinion 49 and having a slotted arm, a slide, and a rod pivoted to said slide and adjustably secured in said slot, as and for the purpose set forth.

44. The combination, with the twisting-heads, oscillating shaft 48, and segmental gear 50, having an arm, 53, of a slide, 57, having a roller engaging a groove in cam 8, and 60 a rod connecting said slide with said arm to cause the oscillation of the twisting-heads.

45. The combination, with the twisting-heads, shaft 48, segmental gear 50, having slotted arm 53, and gage 61, of slide 56 and arm 65 55, pivoted to said slide and adjustably secured to said arm, whereby the amount of rotation imparted to the twisting-heads may be accurately regulated.

46. The combination, with stationary standard 11 and movable standards 12 and 13, carrying the holding-jaws and twisting-heads, of the sliding feeding device carrying jaws, mechanism, substantially as described and shown, to cause said jaws to grasp and release 70 the wire at proper times, and cutters whereby the wires are severed.

47. The holding-jaws, and twisting heads located midway between the holding-jaws and the cutters, in combination with the sliding 80 feeding device and mechanism, substantially as described, for adjusting the holding-jaws and the twisting-heads in proper relation to each other and adjusting the throw of the feeding device to correspond therewith. 85

48. The combination, with stationary and movable standards, the holding-jaws, mechanism, substantially as described and shown, for operating said jaws, and the twisting-heads, of a segmental gear having a slotted 90 arm, by which the twisting-heads are operated, and means, substantially as described, for regulating the oscillation of the segmental gear, whereby more or less twist may be imparted to the wire, as may be required. 95

49. The combination, with the holding-jaws, the twisting-heads, and the cutters, of the sliding feeding device carrying jaws 79, mechanism, substantially as described, for adjusting the throw of the feeding device, and adjustable fingers 84 and 85, carried by sliding shaft 86, whereby the opening and closing of the jaws may be regulated. 100

In testimony whereof I affix my signature in presence of two witnesses.
